Term of patent 14 years

(Cl. D92—1)

F25-2F25-1F25-3

This application is a continuation-in-part of our co-pending application Serial Number D. 31,609, filed July 26, 1954, and which is now abandoned.

We claim:

The ornamental design for a chenille fabric, as shown and described.
